UNITED STATES PATENT OFFICE.

FELIX KIRSCHNER, OF VIENNA, AUSTRIA.

APPARATUS FOR ELECTROGALVANIZING.

Application filed January 31, 1923. Serial No. 616,041.

To all whom it may concern:

Be it known that I, FELIX KIRSCHNER, citizen of the Republic of Switzerland, residing at Vienna, XVII, Dornbacherstrasse 572, Republic of Austria, have invented certain new and useful Improvements in Apparatus for Electrogalvanizing, of which the following is a specification.

It has already been proposed to use apparatus for electrogalvanizing in which the articles to be galvanized hang motionless in an electrolyte which is kept in motion, and also to use baths in which the articles to be galvanized are kept in motion whilst the electrolyte is either motionless or kept in motion. Electrogalvanizing devices are also known in which a circulation of the electrolyte is effected by means of heating devices. With these baths, however, when the articles travel through them very rapidly and high currents are employed, a high quality galvanization cannot be relied upon with certainty. In the galvanization of wire, strip iron and the like upon a large scale it is very important to secure a high quality of galvanization with reliability and rapidity not only for economical reasons but also upon technical grounds.

In the rapid galvanizing of wires, strip iron and the like upon a large scale the goods to be galvanized must be treated in a continuous operation both before and after galvanizing. This necessitates great efficiency and certainty of operation of the galvanic bath by reason of the great speed at which the articles travel through the bath, particularly where a heavy galvanic coating of metal is to be applied. Besides this, the speed of operation of the apparatus for the preliminary and subsequent treatment can easily be increased, whilst the electrogalvanizing process itself, according to methods hitherto known, cannot be made to keep pace with the increased speed of operation of this apparatus.

The problem of the rapid galvanizing of articles traveling rapidly through the galvanizing bath is solved according to the present invention by providing the bath with a trough preferably in the form of a gutter to which are connected one or more circulating channels or conduits of

special construction in which are arranged devices such as propellers, for example, for producing an energetic current in the electrolyte in a direction opposite to that of the traveling goods.

In the accompanying drawings the invention is illustrated in one form of construction.

Figs. 1 and 2 show diagrammatically an electrogalvanizing apparatus in sectional elevation and plan respectively.

Figs. 3 and 4 show the right hand end of the apparatus on a larger scale in sectional elevation and plan respectively.

Figs. 5 and 6 show the left hand end of the apparatus, on the same scale as Figs. 3 and 4, in sectional elevation and plan respectively.

Fig. 7 is a section on the line VII—VII of Fig. 3.

Fig. 8 is a section of line VIII—VIII of Fig. 3.

Figs. 9 and 10 show details on a still larger scale in sectional side view and end elevation.

The bath consists of a narrow, shallow and comparatively long gutter-shaped trough 1. Rollers 2 and 3 are provided for guiding the articles α travelling through the bath. The rollers 2 and 3 are driven from a driving shaft 4 by means of transmission wheels 5 and 6.

To the bottom of the trough is connected a circulating conduit 10. This consists of a down pipe 11 and a rising pipe 12. Through the rising pipe 12, in the construction illustrated in the drawings, there passes an auxiliary pipe 13, which is supplied with steam or hot water. At the end of the auxiliary pipe 13 is provided a condenser 14. The heating of the circulating conduit 10 can be effected in other ways. The right hand end of the trough is provided with a lateral extension 15 (Fig. 7) at the bottom of which is inserted the union with the down pipe 11. In the down pipe 11 is mounted a device such as a propeller 16 for circulating the liquid in the bath and this may be driven either directly or indirectly. Behind the down pipe 11 there is provided a filter 18 which is mounted in the extension 15 so as to be interchangeable.

At the lowest point *b* of the circulating pipe 10 there is provided a run off cock not shown in the drawings, by means of which the bath can be emptied when the 5 galvanizing liquid is to be renewed.

The cathode is formed of the travelling articles *x*. The anodes consist of plates 20, 21 (Figs. 3 and 8) which in the construction illustrated in the drawings are arranged 10 above and below the articles *x*. The lower plates rest upon the trough lining 22 which consists of insulating material. The upper plates are carried by a grid 23 the bars of which consist of glass. The bars of the 15 grid are carried in bearings 24 let into the sides of the trough. The supply of current to the anodes 20, 21 takes place through leads 25, 26 (Fig. 8) which are connected by means of terminal screws to the current 20 supply bars 30. The supply of current to the cathode takes place through the application of suitable rubbing contacts upon the travelling articles *x*. The cathode can with 25 advantage be put under current by the current being supplied to the shafts 2', 3' of the guide rollers 2, 3, and conveyed to the cathode through the surfaces of the rollers which are of conducting material. In this 30 case it is desirable that the rollers 2, 3 should be screened from the anodes by screens 34 (Fig. 1) of insulating material such as glass.

The articles *x* during their passage through the bath are supported upon a 35 number of devices 40. These supporting devices consist according to the present invention of bodies which do not present extensive unbroken surfaces, and consequently offer as little resistance as possible 40 to the flow of the electrolyte. A suitable supporting device may for example consist of a cage-like reel or roller of suitable construction, which is provided with insulating material upon the surfaces which 45 come in contact with the articles. The supporting device illustrated in Figs. 9 and 10 consists for example of a cage-like roller having a number of arms 41 the shaft 42 of which is mounted in bearings 43 open 50 at one side. Upon the arms 41 are mounted insulating bodies 42 preferably in the form of glass tubes, glass rings or the like.

In the apparatus for electrogalvanizing above described, which may be used for 55 example for tinning rapidly travelling wire, metal strip or table articles, the cathode consists of previously pickled and properly cleaned wire, strip iron or the like, the anodes consisting of tin and the electrolyte 60 of a fluid suitable for carrying out galvanic tinning. The wires 25, 26 which lead to the anodes also consist of tin. They are insulated at the points where they dip into the bath by insulating means 31.

65 Assuming that the articles are travelling

through the trough 1 from right to left in Fig. 1 at considerable speed and that the trough is filled with electrolyte, the bath is put under current and the propeller is operated, there is now an extremely energetic circulation of the electrolyte within 70 the apparatus in the direction indicated by the arrows in Fig. 1. The result of this is that the rapidly travelling articles are subjected to an energetic washing by the 75 electrolyte in a direction which is opposite to that of the movement of the articles through the bath. Since the circulating conduit is provided with heating means it is also possible as required to work with the 80 electrolyte at different temperatures without injuriously heating it. At the same time the effect of the heating is to increase the speed of circulation of the electrolyte as in known galvanic baths using hot water 85 for heating. The energetic circulation of the electrolyte is not materially interfered with either by the electrodes lying in the bath nor by the bodies which support the goods. The apparatus above described complies with all theoretical and practical requirements for obtaining heavy metal coatings on rapidly traveling articles and is 90 besides of simple construction and great reliability in operation. 95

What I claim is:

1. An apparatus for electrogalvanizing, comprising a trough for the electrolyte and through which the articles to be galvanized are adapted to travel, a conduit having its 100 opposite ends connected to the trough adjacent the opposite ends of the latter, and means in said conduit for effecting forced circulation of the electrolyte through the trough in a direction opposite that in which 105 the articles to be galvanized travel.

2. In an apparatus for electrogalvanizing the combination with the elements claimed in claim 1, of means in the conduit for heating the electrolyte. 110

3. An apparatus for electrogalvanizing, comprising a trough for the electrolyte and through which the articles to be galvanized are adapted to travel, a conduit associated with said trough, said conduit comprising a portion leading down from and connected to one end of said trough, a portion leading up to and connected to the opposite end of said trough and an intermediate portion, and means in the first mentioned portion of the conduit for effecting forced circulation of the electrolyte through the trough in a direction opposite that in which the articles to be galvanized travel. 115

4. An apparatus for electrogalvanizing, comprising a trough for the electrolyte and through which the articles to be galvanized are adapted to travel, a conduit associated with said trough, said conduit being substantially U-shaped and having its legs con- 120 125 130

nected to opposite ends of said trough, and for supporting the articles to be galvanized 10
a propeller in one of the legs of the conduit within the trough.

and adapted to effect forced circulation of
the electrolyte through the trough in a di-

5 rection opposite that in which the articles
to be galvanized travel.

5. In an apparatus for electrogalvanizing,
the combination with the elements
claimed in claim 1, of insulating spiders

for supporting the articles to be galvanized 10
within the trough.

In testimony whereof I affix my signa-
ture in the presence of two witnesses.

FELIX KIRSCHNER.
